CLAIM

The ornamental design for a bottle, as shown and described.

DESCRIPTION

The nature of this product is as a bottle for holding and dispensing a sprayable liquid material such as an insect repellent, an insect repellent, an insecticide, a cleaner, or a fragrance.

FIG. 1 is a top, front, and left side perspective view of a first embodiment of a bottle embodying our new design;

FIG. 2 is a front elevational view thereof, the rear elevational view being a mirror image;

FIG. 3 is a left side elevational view thereof, the right side elevational view being a mirror image;

FIG. 4 is a top plan view thereof;

FIG. 5 is a top, front, and left side perspective view thereof, shown with environment of an unclaimed pump sprayer and cap;

FIG. 6 is a top, front, and left side perspective view of a second embodiment of a bottle embodying our new design;

FIG. 7 is a front elevational view thereof, the rear elevational view being a mirror image;

FIG. 8 is a left side elevational view thereof, the right side elevational view being a mirror image;

FIG. 9 is a top plan view thereof; and,

FIG. 10 is a top, front, and left side perspective view thereof, shown with environment of an unclaimed pump sprayer and cap.

The broken lines shown in the drawings are for environmental purposes only and form no part of the claimed design.
